CLAIM

The ornamental design for a combined megaphone and flashlight, as shown and described.

DESCRIPTION

FIG. 1 is a perspective view of a combined megaphone and flashlight, showing my new design;

FIG. 2 is a right side view thereof, the left side view being a mirror image thereof;

FIG. 3 is a top view thereof;

FIG. 4 is a front view thereof; and,

FIG. 5 is a rear view thereof.

The broken lines in the figures illustrate the portions of the design that form no part of the claimed design.

1 Claim, 3 Drawing Sheets

FIG. 1

Continuation of application filed under 35 U.S.C. 120, 141, 365, or 371, which claims the benefit of earlier filing date, and/or right to priority, of:

FIG. 3

FIG. 2

FIG. 5

FIG. 4
